TRANSIT CONCRETE MIXER

Evan S. Prichard, La Canada, Calif., assignor to Cook Bros. Equipment Co., Los Angeles, Calif., a corporation of California

Application October 10, 1955, Serial No. 38,314

Term of patent 14 years

(Cl. D14—3)

FIG. 1

Fig. 1 is a side elevational view of the transit concrete mixer showing my new design.

Fig. 2 is a top plan view of the transit concrete mixer.

Fig. 3 is a front end elevational view of the transit concrete mixer.

The dominant features of my design reside in those portions shown in full lines.

I claim:

The ornamental design for a transit concrete mixer, as shown and described.
